CLAIM

I claim the ornamental design for an ice cream maker, as shown and described.

DESCRIPTION

FIG. 1 is a perspective view of an ice cream maker showing my new design;

FIG. 2 is a rear elevation view thereof;

FIG. 3 is a front elevation view thereof;

FIG. 4 is a bottom plan view thereof;

FIG. 5 is a top plan view thereof;

FIG. 6 is a right side view thereof;

FIG. 7 is a left side view thereof;

FIG. 8 is a perspective view of another embodiment of the ice cream maker shown in FIG. 1;

FIG. 9 is a front elevation view thereof;

FIG. 10 is a top plan view thereof;

FIG. 11 is a bottom plan view thereof;

FIG. 12 is a rear elevation view thereof;

FIG. 13 is a right side view thereof;

FIG. 14 is a left side view thereof;

FIG. 15 is a perspective view of another embodiment of the ice cream maker shown in FIG. 1;

FIG. 16 is a front elevation view thereof;

FIG. 17 is a top plan view thereof;

FIG. 18 is a bottom plan view thereof;

FIG. 19 is a rear elevation view thereof;

FIG. 20 is a right side view thereof; and,

FIG. 21 is a left side view thereof.
